UNITED STATES PATENT OFFICE.

AUGUST T. NELSON, OF MILWAUKEE, WISCONSIN.

MECHANISM FOR LOWERING BOATS.

Application filed April 18, 1922, Serial No. 554,870. Renewed November 19, 1925.

This invention relates to means for lowering life-boats from ships, and has for its objects the provision of mechanism of simple form and construction which may be speedily operated to lower the filled boats from the ship's decks to the water on an even keel and without danger of tipping or overturning, or of being injured or destroyed by being thrown against the side of the vessel by the roll of the same or the action of the waves, as frequently occurs when the boat is suspended by cables from davits.

With these and other objects in view my invention consists of mechanism of improved form and construction comprising a supporting device or carrier for the boats, adapted to be supported on the deck in position to receive the boats to be lowered, and being movable outwardly to overhang the ship's side, and being movable also downwardly to lower the boats to the water.

In the more specific embodiment of the invention, the boat support or carrier comprises a horizontal boat supporting structure movable in vertical guides in a frame or carriage which latter is movable inwardly and outwardly on the deck, the ship's side being provided with an upright guideway with which the guides on the carriage will register when the carriage is moved outwardly; whereby the boat carrier may enter the upright guideway and be lowered along the ship's side to carry the boat to the water. When the carrier reaches the water and is sufficiently submerged to disengage the boat, the latter will float away from the same. The carrier is then moved upwardly in the upright guideway, and the upward movement continuing it will enter the guides in the carriage and will leave the upright guideway, whereupon the carriage and boat carrier are moved inwardly on the deck to their former position, with the carrier ready to receive the next boat to be lowered. Means are provided, as will be described in detail hereinafter, for moving the carriage and connected boat carrier outwardly and inwardly on the deck, and for moving the boat carrier up and down in the guideway in the ship's side, which means may be operated by power or by hand, and may be so controlled that the carrier may be arrested at the different decks to receive boats from the same.

As a further feature of my invention, the

boats are stored on the deck on tracks or ways which may extend both fore-and-aft and athwartships, the said tracks or ways leading to the point or points at which the movable boat carrier is supported in its receiving position, so that the boats on the tracks may be moved one after the other onto the boat carrier, and the latter moved outwardly to lowering position, and then downwardly to lower the boats in succession to the water.

In the accompanying drawings:

Fig. 1 is a top plan view of the boat lowering mechanism, with the boat carrier in receiving position.

Fig. 2 is an end elevation of the same with parts broken away to expose other parts to view.

Fig. 3 is a front elevation of the boat lowering mechanism.

Fig. 4 is a view similar to Fig. 3, the boat carrier having been moved outwardly to lowering position, and being shown partially lowered.

Fig. 5 is a diagrammatic view showing particularly how the boats are taken from the lower decks, and also how the boat is launched from the carrier.

Fig. 6 is a plan view of the upper deck showing how the boats to be lowered are stored thereon.

Fig. 7 is a similar view of one of the lower decks showing how the boats may be transferred therefrom to the boat carrier in position at the lower deck.

Fig. 8 is a top plan view of one of the boat holding cradles.

Fig. 9 is a side elevation of the same.

Fig. 10 is an end elevation of the same.

Fig. 11 is an elevation of one of the locking devices for holding the cradles in definite positions on the supporting track.

Fig. 12 is a fragmentary view showing the form of the carrier wheels which are employed on the cradles stored on the transverse track.

Fig. 13 is a horizontal transverse sectional plan view on the line 13—13 of Fig. 3.

Referring to the drawings:

1 designates a portion of a ship provided with the usual upper deck 2 and the lower decks 3. 4 designates my improved boat lowering mechanism of which there may be one or more, according to the size of the ship, the number of life boats which are car-

ried, and other conditions encountered in practice. The boat lowering mechanism, in the present instance comprises a carriage 5 supported on the deck and movable thereon from an inner to an outer position, a boat carrier 6 connected with the carriage to move outwardly and inwardly with it, and adapted to receive the boat to be lowered, and an upright guideway 7 on the side of the ship to receive the boat carrier when it is moved outwardly by the carriage, so that the carrier can be moved down the guideway to lower the boat to the water. The movements of these parts are effected and controlled by an operating mechanism which will be fully described later on; and in lowering a boat, the carriage in its inner location, positions the boat carrier so that a boat from the deck may be pushed endwise onto the carrier. The passengers then enter the boat, and the carriage is moved to its outer position, which will cause the carrier, with the loaded boat supported thereon, to overhang the side of the ship. The boat carrier is then lowered down the guideway on the ship's side and carries the loaded boat to the water, and when the carrier is sufficiently submerged, the buoyant effect of the water will float the boat and the latter can be pushed from the side of the ship and be thus launched. The carrier is then raised to its former position and becomes interlocked with the carriage, and the latter is finally moved back on the deck to its inner position, with the carrier in position to receive the next boat to be lowered.

The boats to be lowered are stored on the deck in cradles 8 which are provided with wheels 9 adapted to travel on tracks or ways on the deck. These tracks lead to the point or points on the deck where the boat lowering mechanism is located, and terminate in line with the boat carrier when the latter is in its inner receiving position, so that the cradles with the boats supported thereon may be moved from the track onto the carrier in succession, and be successively lowered to the water.

The carriage 5 in the present instance consists of a horizontal table or platform 11 having rollers 12 mounted thereon which travel in parallel ways or guides 13, 13 on the deck and extending athwartships thereof, the said guides terminating at their outer ends at the outer edge of the deck. At the outer edge of the platform 11, are fixed two columns 14, having vertical guideways 15, by means of which the boat carrier is interlocked with the carriage to move with it, and is permitted to be moved vertically relatively to it.

The boat carrier 6 in the present instance comprises a horizontal supporting portion to support the cradles 8, and two standards 17, extending upwardly from the inner side of

the supporting portion and having rollers 18, 18 mounted thereon to travel in the guideways 15 in the carriage columns, the form and relation of the rollers and guideways 15 being such that the carrier will be interlocked with the carriage so as to move back and forth with it, but may slide vertically relatively to the carriage, and in its downward movement will disengage from the carriage and enter the upright guideway in the ship's side. The horizontal portion of the boat carrier is formed of two horizontal parallel arms 16 extending outwardly from the lower ends of the standards 17, on which arms are fixed track rails 19 which receive the wheels of the cradles 8 and give support to the cradles. The supporting surfaces of these rails are slightly below the upper edges of the arms 16, the purpose of which will presently appear. Rollers 20, are mounted on the arms 16 and travel on the deck, and thus support the carrier in its movements outwardly and inwardly with the carriage.

The guideway 7 on the ship's side is preferably formed by means of two rails 7^a, firmly fastened to the side of the ship and extending vertically parallel to each other, the said rails being recessed in their adjacent edges to form grooves 7^b which receive and guide the rollers 18 on the standards of the boat carrier. These guiding grooves are open at their upper and lower ends and at the inner sides, and they terminate at their upper ends in such position that they will register with and form continuations of the guideways 15 in the carriage columns, when the carriage is in its outer position with the boat carrier overhanging the ship's side. As a result of this arrangement and construction, when the boat carrier is in its outer lowering position, it will when moved downwardly, disengage from the guides in the carriage and will enter the guideway on the ship's side and be guided thereby in lowering the boat to the water; and when moved upwardly after the boat is floated, the carrier will again enter the carriage guides and become interlocked therewith, so that it will be moved back to boat receiving position when the carriage is moved inwardly.

The carriage may be moved outwardly and inwardly by any suitable and appropriate means. In the particular form of the invention illustrated, these movements are effected by means of two parallel racks 21 fixed to the deck and engaged by pinions 22 fixed to a shaft 23 extending crosswise of the carriage and mounted in bearings thereon. The shaft is geared to an electric motor 24 sustained by the carriage platform and controlled by a suitable controller 25. Means are provided for operating the shaft 23 by hand in the event, for instance, that the power means are disabled. For this purpose a vertical shaft 26 is suitably geared

to the shaft 28 and is operated by a hand crank 27 on a horizontal shaft 28 geared to the shaft 26.

The boat carrier may be moved up and down by any suitable means. In the present instance, an electric motor 29 is provided which is sustained by the carriage platform and geared by gears 30 and 31 to an operating shaft 32 extending crosswise of the plat-
10 form and mounted in bearings thereon. Two winding drums 33 are fixed to the shaft, re-
spectively at its opposite ends, and have hoisting cables or bands 34 wound thereon, which cables pass around guide pulleys 35
15 journaled on the upper ends of the columns 14 of the carriage, the said cables being connected at their ends to the upper ends of the standards 17 of the boat carrier. The motor 29 is controlled by a suitable con-
20 troller 29^a, and two hand operated brake mechanisms 36 are applied to the shaft 32 to properly control the descent of the car-
rier. Means are provided for operating the hoisting drums by hand, which is effected
25 through the medium of a horizontal shaft 37 mounted in bearings in the carriage plat-
form and provided with suitable hand cranks 38, the said shaft being geared to the shaft
32 by a train of gears 32^a.

30 Referring to Fig. 6 which shows the plan of storage of the boats on the upper deck, it will be seen that in the present instance there are provided an outer fore-and-aft extending track 10^a for supporting an outer line of
35 boats, an inner track 10^b extending parallel with the outer track to support an inner line of boats, and a cross track 10^c to support additional boats. The outer track is in two sections disposed on either side of the boat
40 lowering mechanism, the said sections termin-
inating at their inner ends at points in line with the track on the carrier when the latter is in its inner receiving position, so that the cradles supported on the track sections can
45 be run onto the carrier from both sides of the same. The inner track 10^b is likewise in two sections on either side of the boat lowering mechanism, the inner ends of each section being curved outwardly as at 10^d to join
50 the terminal ends of the outer sections, and thus guide the cradles on the inner track sections to the boat carrier in its receiving position. The cross track 10^c leads to the outer track, so that the cradles on the cross
55 track may be transferred to the outer track section and then run along the same onto the carrier track. It is understood that in the storage of the boats, they are supported by and rest on the cradles which are in turn
60 movably sustained by the tracks as described.

The cradles 8 consist each of two parallel side bars 8^a which are connected at their ends by end plate 8^b which are socketed to follow the transverse curvature of the boat
65 respectively at its front and rear, so that

when the boat is seated in the cradle, it will by reason of the swell of its sides be pre-
vented from shifting either in a fore-and-aft
direction or laterally. The wheels of those
70 cradles which are stored on the transverse
track 10^c are swiveled to the cradle as shown
in Fig. 12 so that the wheels may turn on
the axis of the swivel and follow the chang-
ing direction of the track rails when the
75 cradle is transferred from the cross track to
the fore-and-aft track.

The cradles are releasably held at definite
80 positions on the deck tracks by means of
locking dogs 39, see Fig. 11, which dogs are
carried by shafts 40 mounted in bearings on
the deck at the points where the cradles are
located. Each shaft has fixed to it an oper-
ating lever 41 by which the dog may be
rocked so as to engage over a bar 42 fixed
85 to the underside of each cradle, and thereby
hold the cradle in its storing position. When
a boat is to be passed onto the boat carrier
for lowering, the handle 41 associated with
90 the cradle on which the boat is supported, is
rocked to the right in Fig. 11 thereby dis-
engaging the connected dog from the cross
bar of the cradle and releasing the same.

The terminal portions of the track sections
10^a are sloped upwardly as shown at 43 in
Fig. 3, so as to stand somewhat above the
horizontal arms 16 of the boat carrier frame.
This is for the purpose of facilitating the
passage of the cradles onto the carrier track,
in which operation the forward wheels of
the cradle, after leaving the end of the slop-
ing track, will drop down onto the carrier
track, and as the cradle reaches its final pos-
ition on the carrier, the rear wheels will also
drop down and rest on the carrier track,
and in this position the cradle will be held
from endwise escape by the two arms 16
extending along the outer ends of the cradle.

In order that when the boat supported
by the cradle is positioned on the boat car-
rier for lowering, the boat will be prevent-
ed from tipping or turning laterally out-
ward, I provide a locking device of such
110 form that the boat will be automatically in-
terlocked with the carrier when the cradle
is pushed onto the carrier, and will be auto-
matically released when the carrier reaches
the water and is submerged sufficiently to
float the boat. This locking device in the
115 present instance consists of a plate 44 fixed
to a horizontal cross bar 45 connected at
its ends to the standards of the boat car-
rier. The plate extends outwardly and
then upwardly in the form of a lip 46. On
the side of the boat a cooperating plate 47
is fixed which is provided with a down-
wardly extending overhanging lip 48. The
relation and size of the parts is such that
when the cradle, with the boat supported
thereon, passes onto the carrier track, the
120 downwardly extending lip on the boat will
125

pass behind the upwardly extending lip on the carrier, and the two will thus become interlocked against lateral displacement. When the carrier is lowered and is submerged so as to float the boat, these lips will become disengaged by the relative vertical movements of the boat and carrier, and the boat will be released.

The cradles are preferably formed of wood so that when the boat is floated the cradle will also float away and thus avoid the necessity of returning the cradle to the deck on the return of the carrier for the next boat. If desired, however, means may be provided for locking the cradle on the carrier to prevent its loss in the launching operation. In lowering the boats where the ship is to be abandoned, the cradles would be permitted to float away in the launching operation, and would serve as a raft to enable any persons in the water to cling to them and keep afloat.

I propose in order to enable the passengers to readily enter the boat when the latter is supported on the boat carrier ready for lowering, to provide a flight of steps 49 see Figs. 2 and 3. These steps are supported by the carriage platform adjacent the outer edge of the same, with the upper step terminating at about the level of the gunwale of the boat.

In order that boats from the lower decks may be passed onto the boat carrier, I propose to provide the lower decks with a track 50 see Fig. 7 to give support, in a manner similar to the tracks on the upper deck, to the boat holding cradles. This track is provided with a terminal portion in the form of a track section 51 which is hinged 40 as at 52 to the main portion of the track, to be swung outwardly and register with the carrier track when the carrier is in position at the lower deck. In taking a boat from the lower deck, the carrier is lowered 45 to the deck and there arrested as shown by dotted lines in Fig. 5. The terminal section 51 of the lower deck track is then swung outwardly to register with the track on the carrier as shown in Fig. 7 and the cradle is run along the outwardly positioned track section and transferred to the carrier track. The downward movement of the carrier is then continued and the boat lowered to the water. An indicator A may be provided 55 on the carriage and suitably geared to the boat carrier to show when the carrier arrives at the lower decks, so that the carrier may be arrested at the proper point to receive the boats from the lower decks.

In order to protect the rails 7^a forming the upright guideway on the ship's side, from injury, and in order to prevent the guiding grooves in the rails from becoming clogged with ice or other obstructions, I provide a temporary filler member between

the rails, which when the boat lowering mechanism is to be employed, will be removed from the rails so as to free the guideway. In the present instance this filler member is in the form of a plate or board 70 52 of wood, with an outer sheathing of sheet iron. The edges of the plate are formed with tongues to fit in the grooves in the rails, and the outer face of the plate extends flush with the outer faces of the rails as 75 shown in Fig. 13. The plate is suspended in its operative position between the rails, by means of a bridle 53 attached to the upper end of the plate and having connected with it a cable 54 leading to the deck and 80 secured thereto by a releasable fastening device 55. When the boat lowering mechanism is to be used, the fastening device 55 is operated to release the cable, and the weight of the plate will carry the same down 85 in the guideway and it will pass outwardly from the lower end of the same. In the event that it is desired to prevent the loss of the plate, it may be drawn upwardly out of the guideway by means of a cable 56 attached to the cable 54 and leading upwardly and passed around a sheave 57 on a horizontal arm 58 projecting forwardly from a cross bar connected to the upper ends of the carrier columns, and thence to the deck where it may be operated by means of a winch or otherwise.

In the event that the ship is down by the head or stern and the storing tracks are correspondingly inclined, the cradles, with the boats supported thereon, may be readily passed onto the boat carrier, I propose to provide a cable or line 59 which is passed around a snatch block or guide 60 on the deck in line with the storing track, and is adapted at its end to be hitched to the cradle. The said line is lead inwardly so that it may be operated by a winch 61 or otherwise on the carriage platform, to haul the cradle and supported boat up the inclined track and onto the track of the boat carrier. As shown by dotted lines in Fig. 1 the snatch block may be employed at either side of the boat lowering mechanism to haul the cradles from either of the track sections 110 according to the position of the ship.

In the accompanying drawings I have shown the ship equipped with but one boat lowering mechanism. It will be understood however that a number of these mechanisms may be employed according to the number of boats to be handled; and further it will be understood that tracks for storing the boats on the upper deck may be arranged on both sides thereof, and at both ends of the same.

In the use of the device for launching a boat, for instance to rescue a man overboard, or for other purposes, where the boat would be returned to the carrier and again elevated to the deck, I propose to provide the carrier

standards with cleats 62, as shown in Figs. 3 and 5, to enable a line from the returning boat to be fastened to the carrier and properly positioned so that on the elevation of the carrier from its submerged position, the boat will be received by the same and raised with the carrier to the deck.

The gear trains 30 and 31 between the motor 29 and operating shaft 32, as referred to hereinbefore, are arranged so as to drive the shaft under different gear ratios; and a gear shifting device 31^a is provided to shift the gear so as to change the ratios. A clutch mechanism 63, see Fig. 1, is provided for the operating shaft 32 so as to connect or disconnect the winding drums from the motor.

In the accompanying drawings and foregoing description I have illustrated my invention in the particular detailed form and construction which I prefer to adopt. It will be manifest however that these details may be variously changed and modified by the skilled mechanic without departing from the spirit of the invention; and further it will be understood that the invention is not limited to any particular form or construction of the parts except in so far as such limitations are specified in the claims.

Having thus described my invention, what I claim is:

1. In combination with a ship having means on its deck to guide a life boat in a definite path, a boat lowering mechanism comprising a boat carrier supported by the deck normally in an inner position in line with the path of movement of the life boat to receive a boat from said path, said carrier being movable outwardly to a lowering position, and a guideway on the ship's side in position to receive the carrier in its outer position, and down which guideway the carrier is movably guided to lower the boat.

2. In combination with a ship having means on its deck to guide a boat supporting cradle in a definite path, a boat lowering mechanism comprising a boat carrier supported by the deck normally in an inner position in line with the path of movement of the cradle to receive the cradle from said path, said carrier being movable outwardly to a lowering position, and a guideway on the ship's side in position to receive the carrier in its outer position, and down which the carrier is movably guided to lower the boat.

3. In combination with a ship having means on its deck to guide a life boat in a definite path, a boat lowering mechanism comprising a carriage movable outwardly and inwardly on the deck, a boat carrier movable with the carriage and adapted when the carriage is in an inner position to register with the path of movement of the boat to receive the boat from said path, and a guideway on the ship's side in position

to receive the carrier in its outer position, and down which the carrier is movably guided to lower the boat.

4. In combination with a ship, a boat lowering mechanism comprising a carriage movable outwardly and inwardly on the ship's deck, a boat carrier adapted to receive the boat to be lowered and slidably interlocked with the carriage to move relatively to the same up and down, a guideway on the side of the ship in position to receive the boat carrier when the carriage is moved outwardly, and means for moving the carrier up and down in said guideway.

5. In combination with a ship, a boat lowering mechanism comprising a carriage movable horizontally on the ship's deck outwardly and inwardly and provided with upright guides, a boat carrier mounted for movement in said guides, an upright guideway on the side of the ship in position to register with the guides of the carriage when the latter is moved outwardly and to receive the carrier, means for moving the carriage outwardly and inwardly, and means for moving the carrier up and down.

6. In combination with a ship having a deck provided with horizontal guides, a carriage movable on said guides outwardly and inwardly, means for moving said carriage, upright guides on the carriage, an upright guideway on the side of the ship in position to register with the carriage guides when the carriage is moved outwardly, a boat carrier movable in the guides on the carriage and in the guideway on the side of the ship, and means for moving the carrier in said guides.

7. In combination with a ship, a carriage movable outwardly and inwardly on the deck of the same, a boat carrier detachably interlocked with the carriage to move outwardly and inwardly therewith and movable vertically relatively thereto to disengage the carriage, an upright guideway on the side of the ship in position to receive the carrier when disengaged from the carriage, and means for moving the carrier in said guideway.

8. In combination with a ship having a deck, a track on said deck to movably sustain the boat to be lowered, a boat carrier supported on the deck in position to receive the boat directly from said track, said carrier being movable outwardly from its receiving position to a lowering position, an upright guideway extending along the side of the ship in position to receive the carrier when the latter is moved outwardly, means for moving the carrier outwardly, and means for moving the same up and down on said guideway.

9. In combination with a ship having a deck, a track on said deck, a cradle movable on the track and adapted to receive the boat

- to be lowered, a boat carrier supported on the deck and provided with a track in position to receive the cradle from the first mentioned track, said carrier being movable outwardly from its receiving position to a lowering position, an upright guideway extending along the side of the ship in position to receive the carrier when moved outwardly, means for moving the carrier outwardly, and means for moving the carrier on said guideway.
10. In combination with a ship provided with upper and lower decks, a boat carrier adapted to receive a boat from the upper deck and movable down the ship's side to the water, means for moving said carrier and arresting the same with a predetermined definite position at the lower deck, and a track on the lower deck to movably support the boat to be lowered therefrom, said track being provided with a terminal portion adapted to lead to the carrier when positioned at said predetermined definite position at the lower deck.
15. In combination with a ship provided with upper and lower decks, a boat carrier adapted to receive a boat from the upper deck and movable down the ship's side to the water, means for moving said carrier downwardly and arresting the same at the lower deck, a track on the lower deck to movably support the boat to be lowered therefrom, and a terminal switch on said track adapted to be swung outwardly to guide the boat to the carrier when positioned at the lower deck.
20. In combination with a ship provided with upper and lower decks, a boat carrier adapted to receive a boat from the upper deck and movable down the ship's side to the water, and an interlocking connection between the inner side of the boat and the carrier to restrain the boat from tipping laterally, said connection being formed to be auto-
25. 11. In combination with a ship provided with upper and lower decks, a boat carrier adapted to receive a boat from the upper deck and movable down the ship's side to the water, means for moving said carrier
30. 35. 40. 45. 50. 55. 60. 65. 70. 75. 80. 85. 90. 95.

matically disengaged to release the boat by 45 a relative vertical movement of the carrier and boat when the latter reaches the water.

13. In a boat lowering mechanism, the combination of a boat carrier adapted to receive the boat in an endwise direction and 50 movable down the ship's side to lower the boat to the water, an upwardly extending lip on the carrier, and a downwardly extending lip on the side of the boat, adapted when the boat is moved endwise onto the carrier, 55 to pass behind the upwardly extending lip.

14. In combination with a ship, upright guide rails on the side of the ship to receive and guide a movable boat lowering carrier, and a filler member seated between the rails 60 to fill out the space between them and being removable therefrom at will.

15. In combination with a ship, upright guide rails on the side of the same to receive and guide a movable boat lowering 65 carrier, a filler member seated between the rails to fill out the space between them, said member being removable from between the guides at will, and a suspension cable attached to said member and leading to the 70 deck.

16. In combination with a ship having a deck provided with a track to movably support a cradle to hold the boat to be lowered, a boat carrier supported in position to receive the cradle from the track, and movable outwardly to overhang the side of the ship and movable also downwardly to lower the boat to the water, a cable guide on the deck in line with the track, a cable passing 80 over said guide and adapted to be connected with the cradle on the track to haul it onto the boat carrier, and a winch on the deck to which the cable is connected.

In testimony whereof, I have affixed my 85 signature hereto.

AUGUST T. NELSON.
